UNITED STATES PATENT OFFICE.

JAMES BRUCE, OF OKLAHOMA CITY, OKLAHOMA.

SWITCH THROWING AND LOCKING DEVICE.

Application filed April 13, 1926. Serial No. 101,744.

This invention relates to a novel switch point throwing and locking device, and has for one of its objects the provision of a device of this character which shall be 5 adapted to exert an equal and positive pressure at relatively spaced points on the switch point in main rail contacting position so as to prevent the possibility of a wheel flange passing between such switch point 10 and the main rail and the consequent wrecking of the train when the switch is closed.

A further object of the invention is the provision of a switch point throwing and locking device which shall be simple, strong 15 and durable and which can be readily applied to any and all switches without making any changes or alterations therein.

With the foregoing and other objects in view, the invention consists of the construction, combination and arrangement of parts hereinafter fully described and claimed, and illustrated in the accompanying drawing, wherein:

Figure 1 is a top plan view illustrating 25 the application of a switch point throwing and locking device constructed in accordance with my invention,

Figure 2 is a detail sectional view taken 30 on the vertical plane indicated by the line 2—2 of Figure 1,

Figure 3 is a similar view taken on the vertical plane indicated by the line 3—3 of Figure 1,

Figure 4 is an elevational view illustrating the manner in which a target located a distance from the switch throwing means may be operated by said means, and

Figure 5 is a sectional view taken on the plane indicated by the line 5—5 of Figure 4.

Corresponding and like parts are referred to in the following description, and designated in the several views of the accompanying drawing, by similar reference characters.

In the drawing, 1 designates the rails of a main track, 2 the rails and 3 the points of a switch, and 4 a switch tie.

In accordance with my invention, the switch points 3 are connected by two bridle 50 or tie rods 5 which are arranged in parallel relation at opposite sides of the tie 4. The rods 5 are secured to the bases of the switch points 3, and are located below and extend in opposite directions beyond the main rails

1. One of the rods 5 is secured to the switch 55 points 3 adjacent their free ends, while the other rod is secured to the points at an appreciable distance beyond the free ends thereof. A casing 6 is secured to the tie 4, and journaled therein is a shaft 7 which occupies a position at right angles to the rods 5. Eccentrics 8 are similarly arranged upon and fixed to the shaft 7. The eccentrics 8 are located within the casing 6 and arranged in alinement with the rods 5. The rods 5 60 extend into the casing 6 and are connected to the eccentrics 8 by straps 9. The rods 5 are of sectional formation, and the sections thereof are connected by turn buckles 10 so as to permit the effective length of 70 the rods to be varied. A lever 11 is connected to the shaft 7 to permit the device to be operated to effect the opening or closing of the switch. The lever 11 is engaged by a latch 12 when the switch is closed and 75 by a latch 13 when the switch is opened. The latches 12 and 13 function to hold the switch in the position into which it has been moved, and they may be provided with locks to prevent tampering with the switch. 80 A target 14 to indicate the position of the switch, of which the shaft 14^a is journaled in the case 6, is operated from the shaft 7 by means of the gears 15.

If desired, the target may be mounted 85 upon the tie 4 at a distance from the case 6, and when this is done the shaft 14^a of the target will be operated from one of the eccentrics 8 by means of a link 16 connected as at 17 to the eccentric and an arm 18 90 extending laterally from the target shaft and connected to the link.

As one of the rods 5 is connected to the switch points 3 adjacent the free ends of the latter and the other at points removed 95 from their free ends, and as the rods are connected to the shaft 7 by eccentrics which exert a similar pressure on each rod, the greater length of one or the other of the switch points will be held positively in contact with its companion main rail, and due thereto there is no possibility of a wheel flange passing between a main rail and the switch point in contact therewith and there is also no possibility of timbers or other 100 obstacles, which usually cause wrecks, lodging between either of the main rails and switch point in contact therewith. The turn 105

buckles 10 permit any play that may occur in the various parts of the device to be taken up.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A switch point throwing device including parallel rods secured to the switch points, a shaft, eccentrics secured to the shaft, straps passing about the eccentrics and secured to the rods, and operating means.

2. A switch point throwing device comprising parallel rods connected to the switch points, said rods being of sectional formation, means adjustably connecting the sections of the rods, a shaft, eccentrics secured

to the shaft, straps passing about the eccentrics and secured to the rods, and a lever 25 secured to the shaft.

3. A device of the character set forth comprising, in combination with switch points, rods secured to the switch points, a shaft, eccentrics secured to the shaft, straps passing about the eccentrics and connected to the rods, a target shaft provided with an arm, a link connected to one of the eccentrics and the arm, and operating means.

4. A device of the character set forth comprising, in combination with switch points, rods secured to the switch points, throwing means for the switch points embodying eccentrics and straps passing about the eccentrics and secured to the rods, a target shaft, and means establishing an operative connection between the target shaft and the switch point throwing means.

In testimony whereof I affix my signature.

JAMES BRUCE.
